UNITED STATES PATENT OFFICE.

CHARLES F. P. ANDERS, OF HOBOKEN, NEW JERSEY, ASSIGNOR, BY DIRECT AND MESNE ASSIGNMENTS, TO EUGENE L. GREENEWALD, OF WASHINGTON, DISTRICT OF COLUMBIA.

VACUUM-BOTTLE.

1,172,247.

Specification of Letters Patent. Patented Feb. 22, 1916.

Application filed November 23, 1910. Serial No. 593,891.

To all whom it may concern:

Be it known that I, CHARLES F. P. ANDERS, a subject of the Emperor of Germany, and resident of Hoboken, in the county of Hudson and State of New Jersey, have invented certain new and useful Improvements in Vacuum-Bottles, of which the following is a specification.

This invention relates to what are known as vacuum bottles and it has been my object not only to simplify the construction, making it easy and less expensive to manufacture the bottles, but also securing better heat insulation, thus retaining the heat in the bottle more effectively than has been done heretofore.

The novel features of my invention will be apparent from the following description taken in connection with the accompanying drawings.

In the drawings, Figure 1 is a vertical section through the device embodying my invention; Fig. 2 is a vertical section through the outer and inner receptacles before they are secured together.

As shown in these drawings, 1 represents the outer wall or receptacle which in this instance is made cylindrical in form having the conical or tapering bottom 2. The inner receptacle 3 is made of substantially the same shape except that it has near its upper end the shoulder 4 formed by an outward bend and leaving what may be termed the neck of the bottle beyond that bend. As shown in Fig. 2, the two receptacles or blanks are formed separately and a coiled spring 5 made of metal is placed in the tapering portion of the outer receptacle and 3' the tapering end of the inner receptacle 40 is inserted in the upper coil of the spring, as shown in Fig. 1. The upper ends of the two receptacles are then secured or fused together at 6, so as to form one complete article, and by this construction it will be observed that the spring 5 serves to center the inner receptacle and to properly support it in position during the uniting operation. I find that when such spring is used in the construction shown, it is not necessary to have any other support or connecting means between the outer and inner receptacles and thus the transmission of heat from the outer to the inner receptacle by conduction in the connecting means is reduced to a minimum. The two receptacles

are preferably made of glass and a space is left between them at all points including the neck and the air is exhausted from this space through the opening 7 which in the beginning is left at the lower point of the outer receptacle. This opening 7 is of course sealed in the usual way after the air is exhausted.

The upper end of the inner receptacle is closed by a stopper or closure 8 which is made hollow and which has the bottom portion 9 extending slightly below the shoulder 4. This closure comprises the end walls 9 and 11 joined by the circular wall 8'. The walls 9 and 11 extend beyond the intermediate wall 8' forming projections or flanges 9' and 11' whereby a groove 10' is formed intermediate the end of the closure 8. An annular packing ring 10 of suitable material surrounds and is carried by the closure 8, and fits in groove 10'. The flange 9' fits the smaller diameter of the receptacle member 3 below the shoulder 4 whereby the packing ring 10 rests on the shoulder 4 and serves to close the bottle tightly and also assists in supporting the closure in the mouth of the bottle. The flanges 9' and 11' are of solid glass, integral with the hollow body, the flange 9' being of smaller diameter than the flange 11'. 85

The top 11 of the closure is originally formed with an opening at the upwardly projecting point 13 for the purpose of exhausting the air within it, but this opening is of course sealed in the usual way when the article is completed as shown. A metal cover 12 is preferably placed over the top of the closure its edge 12' being spun around the upper edge 11' of the closure to hold it in place. This cover serves as a protection. The flange 11' extends outwardly beyond the ring 10 and the peripheral edge 12' of the protecting metal cover 12 engages the upper edge of the packing ring 10 and holds it in place. The cover 12 has a central cup or depression 13' to receive the tip 13 of the wall 11 of the hollow stopper. The bent or curled edge 12' of the protecting cover 12 with the flange 11' provides a wide flange near the upper edge of the closure whereby the closure may rest on the upper edge or lip 6 of the bottle to assist in sealing the opening therein.

It will be understood that my device 110

maintains the contents at practically the same temperature whether hot or cold. The outside heat cannot get in any more than the inside heat can get out.

5 It will be seen that I have provided a double walled container made of two substantially similar blanks. The inner blank is formed initially with a closed bottom, and the outer blank is initially substantially 10 closed at the bottom, with the exception of the small exhaust opening, which is later sealed. Both blanks also are wide-mouthed, *i. e.*, the mouths thereof are substantially the same diameter as the bodies thereof.

15 By making the two receptacles of such shape that the inner receptacle can be inserted through the upper end of the outer receptacle in manufacturing the device the expense and trouble of manufacture is reduced to a minimum and the joints and connections can be easily made.

Having described my invention what I claim and desire to secure by Letters-Patent is,

25 1. A hollow walled container comprising an outer wall, a receptacle member disposed therein and joined thereto at its mouth, said receptacle member having a neck and a body of different diameters joined by a supporting shoulder below said mouth, a closure fitting in the mouth of said receptacle member, and a packing member, and extending to a point substantially opposite said shoulder to close the smaller part of the receptacle 30 member at a point adjacent said shoulder, carried by the closure and fitting between the same and the neck of said receptacle member above said shoulder, said packing member resting on said shoulder.

40 2. A hollow walled container comprising an outer wall, a receptacle member disposed therein and integrally joined thereto at its mouth, said receptacle member having portions of two different diameters joined by a shoulder, the portion having the greater diameter being above the shoulder, a hollow closure fitting in the mouth of the receptacle member and terminating slightly below said shoulder, and a packing ring surrounding 45 the closure and disposed above the said shoulder, said packing ring bearing against and resting on said shoulder whereby the closure is supported on said shoulder by said packing ring.

55 3. A double walled container comprising an inner member, an outer member inclosing the same, said members being integrally united at their mouths, and a spiral member yieldably centering and supporting said inner member at its bottom, said spiral member having the longitudinal axis thereof through the spirals substantially coinciding with the axes of the inner and outer members.

60 4. A double walled container comprising

an inner member, an outer member inclosing the same and separated therefrom by a vacuum space, said members being integrally united at their mouths, and a spiral spring yieldably supporting and centering the inner member within the outer member, said spring engaging the bottom walls of both members and held in place by a part of one of said members.

5. A closure for double walled vessels 75 comprising a hollow exhausted glass body adapted to fit into the mouth of a vessel and having a sealing tip on its upper side and an integral glass flange at the top end thereof, and a metal cover for said sealing tip 80 and the top of said body, said cover having its peripheral edge extending beneath the edge of said integral glass flange, whereby said cover is permanently secured to said body over said sealing tip and said glass 85 flange is provided with a metal protecting edge.

6. A closure for double walled vessels comprising a hollow body adapted to fit into a vessel and having parallel flanges and a 90 sealing tip at its upper end, a packing ring surrounding said body and fitting between said flanges and a protecting metal cover for the top end of said body and the tip and having its edge extending beneath one of 95 said flanges to secure the cover to the body.

7. A vacuum bottle having spaced walls throughout including the neck, a closure spanning the neck, said closure having spaced end walls extending laterally of the 100 closure to provide flanges at the top and bottom thereof, and a circular wall joining said end walls, and a packing ring between said flanges and fitting between the circular wall and the inside surface of the neck of 105 the bottle.

8. A double walled container comprising a one-piece inner receptacle, a one-piece outer wall inclosing the inner receptacle, a device between the bottom of said receptacle 110 and said outer wall, said outer wall being joined to the lip of said receptacle after said device is located in place, said device being capable of yieldingly supporting and centering the receptacle when said receptacle and 115 wall are joined together.

9. A glass vacuum bottle comprising an initially closed - bottom wide - mouth inner glass receptacle member, an initially substantially closed-bottom, wide-mouth outer glass member, said members being fused together at their mouths, and means whereby said initially closed - bottom, wide - mouth glass members are held spaced apart and the inner member is supported and centered 125 within the outer member.

10. A double walled heat insulated bottle comprising an inner glass receptacle member, an outer glass member inclosing said inner member, said members being united at 130

- their mouths and having their bodies separated by a space, said inner member having a portion of reduced diameter at its bottom, and supporting and spacing means located 5 between the bottoms of said members comprising a spring having a part surrounding said reduced portion on the lower end of said inner receptacle member and having a part bearing against said outer member.
- 10 11. A double-walled heat insulated container comprising an inner receptacle member, an outer wall inclosing said receptacle, said receptacle being united to said wall at its mouth and being otherwise separated 15 from said wall by a space, and means yieldingly supporting said receptacle at its bottom comprising a spiral member disposed between the bottom of the outer wall and the bottom of said receptacle and having its longitudinal axis within the spirals extending longitudinally of the longitudinal axes 20 of the outer wall and inner receptacle.
12. A double walled heat insulated container comprising an inner receptacle member, an outer member inclosing said receptacle member and united thereto at its mouth, said outer member having a tapering bottom provided with a sealing tip at its center, and a supporting spring between the bottom of said receptacle member and said outer member and surrounding the axis of said sealing tip. 25
- 30 In testimony whereof I affix my signature in presence of two witnesses.
